SELF ADJUSTING DUMP BUCKET.
APPLICATION FILED DEC 2, 1920.

Patented Aug. 8, 1922.

2 SHEETS—SHEET 2.

UNITED STATES PATENT OFFICE.

GEORGE W. SLAUTER, OF DIXON, ILLINOIS.

SELF-ADJUSTING DUMP BUCKET.

1,425,063.

Specification of Letters Patent. Patented Aug. 8, 1922.

Application filed December 2, 1920. Serial No. 427,894.

To all whom it may concern:

Be it known that I, GEORGE W. SLAUTER, citizen of the United States, residing at Dixon, in the county of Lee and State of Illinois, have invented certain new and useful Improvements in Self-Adjusting Dump Buckets, of which the following is a specification.

This invention relates to certain new and useful improvements in buckets, and it has more particular relation to that class of buckets known as hoisting or excavating buckets.

One of the objects I have in view, is to provide a bucket for removing earth, rock or other material from one point to another, the bucket being so constructed that upon its being lowered to the ground or other suitable support, its bottom, consisting of two hinged sections, automatically falls apart and permits the load to be discharged.

Another object of my invention, is to provide means whereby when the bucket has discharged its contents, and is being raised, its two hinged bottom sections will automatically close, and upon the arrival of the bucket at the loading point, it will be ready to be refilled, without requiring the services of some one to adjust and lock its hinged bottom sections.

With these and other objects in view which may be incident to my improvements, the invention consists in the parts and combinations to be hereinafter set forth and claimed, with the understanding that the several necessary elements comprising my invention, may be varied in construction, proportions and arrangement, without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

Figure 1 is a side elevation of my device showing the bottom sections of the bucket closed.

Figure 2 is an end view thereof.

Figure 3 is also an end view showing the bottom sections open.

Figure 4 is a side view showing the operative mechanism for opening and closing

the bottom sections as it appears when the sections are open.

Figure 5 is a similar view showing said mechanism as it appears when the sections are closed, and

Figure 6 is a detail view of one of the track wheels, upon the sides of the bucket.

Numeral 1, refers to the body of a bucket, made of metal or other suitable material and of a more or less rectangular configuration. The numeral 2, refers to two hinged sections which together form the dumping bottom. These sections are provided with hinges 3—3 secured thereto by bolts or rivets 4—4 and also to the sides of the bucket by similar bolts or rivets 5—5.

The attachment of the hinges is such, as to permit the swinging towards each other, of the two sections until they assume the closed position shown in Figures 1 and 2, or to open outwardly into the position shown in Figure 3.

The bucket is provided above the top of the body with a suspension yoke 6 to be secured to the upper end of arms 8—8, by rivets 9, and the lower ends of said arms, extend somewhat further apart, as they approach the bucket, and are securely riveted thereto by bolts 10.

As seen in Figures 1, 2 and 6 the sides of the bucket are provided with brackets consisting each of a bent metallic plate or casting 11, rigidly secured to the bucket by bolts 12, and from the upper end of the plate or casting is an outwardly and downwardly inclined arm 13, provided near its lower end with an aperture 14; there is also an aperture in the plate 11 and in these apertures is positioned a stud shaft 16 upon which is mounted a track wheel 17. The bracket upon which the wheel 17 is mounted is so constructed as to permit of the travel behind it of the chain or cable presently to be referred to. The purpose of these wheels is to enable the bucket to be run on a track, (not shown), which is arranged to guide the bucket when lowered on it to a position to one side from a perpendicular line under the suspended trolley or other hoisting device and supporting the bucket under a suitable discharge trough or opening leading from a hopper, bin or other arrangement from which the bucket receives the material to be moved.

On each side of the upper edge 18, of the

bucket and between the arms 8, is mounted a plate 20, securely fastened thereto by rivets or bolts 21. The upper central portion of this plate is cut-away so as to furnish supports 22 for a rod or shaft 23, which is mounted therein. Upon the shaft is mounted an idler 24 over which passes the chain or cable 25.

10 The hinged dump sections 2, are each provided at a point nearer the center line of the bucket than the sides with an angular coupling 26, rigidly secured to the outer edge of each section by a rivet or bolt 27. The upper end of this coupling is provided 15 with an eye 28, to which is fitted one of the links of the lower members of the chain 25. As will be seen by reference to Figure 1, these two lower members become united at a point below track wheel 17. The suspension yoke 6 consists of two beams or channel irons 7, secured to the arms 8—8, by bolts or rivets 9, and secured to each other by the end bar 29, (see Fig. 5) rigidly secured thereto by the bolts 30. Pivots 20 mounted within the yoke thus formed and extending upwardly therefrom when the bucket is in closed position, as seen in Figure 2, are bale levers 31, and to the outer 25 end of each is fastened by a clevis 32, or in any suitable manner one end of the chain or cable 25. The lower end of the chain being divided into two members, one attached to each of the bottom sections.

30 Each of these levers 31, at its inner end is provided with a latch plate 33, which is bent downwardly at an angle from the lever, and is constructed and adapted to engage, at the appropriate time, as hereinafter more fully set forth, one of the pawls 34, pivotally mounted upon the beam 7. Each of these pawls is held in position by a chain 35, attached to a trip lever 36, pivotally mounted in angle irons 37, securely fastened to the top of the frame 7, by means of bolts 38. Pivots 40 attached to each of these bale levers 31, are connecting bars 39, the farther end of each of which is bifurcated and into this bifurcation fits and is secured by a bolt 40, what I term a hanger 41. Near 45 the top of this hanger is a hole 42, by means of which the bucket and the mechanism heretofore described, is suitably suspended from a trolley by a cable or rope, as it travels back and forth in its journey from the point of loading, to the point of discharge.

50 The operation of my device is as follows:

55 The bucket being in closed position is filled from the top with the material to be moved and started upon its journey to the point where the same is to be deposited. The weight of the bucket and the material is suspended from the hanger 41 by means of the connecting bars 39; the bale levers 31, the connecting bars 39 being positioned

as shown in Figure 2. When the bucket reaches its destination and it is desired to discharge the material therefrom it is necessary first to lower it until it rests upon the ground or dump pile, or other suitable support. As soon as this is done the strain is taken off the hanger 41; the connecting bars 39 and the bale levers 31 descend, the chains 35 become slack, the pawls 34 engage with the latch plates 33 upon the bale levers 31 and the hoisting mechanism assumes the position shown in Figure 4.

60 In this position the pawls 34 hold the bale lever in open position the weight of the bucket is no longer supported by the chains 25 but such weight as is not supported upon the ground is transferred to the pawls and the bale lever 31, the chains remaining slack. As the bucket is raised the material is discharged, the bottom sections 2 spreading as shown in Figure 3. In its ascent and when it reaches nearly its highest point the trip lever 36, comes in contact with a suitably located projecting bar, (not shown) rigidly fastened to the track frame or other suitable support. This forces downwardly the pivotal end of said lever 36 and raises the outer end to which are attached the chains 35. This in turn releases the pawls 34 from their engagement with the latch plates 33. At the same time the hanger 41, its connecting bars 39 and bale levers 31 rise, the slack is taken out of the cables, the two bottom sections are drawn together, and the hoisting mechanism appears as illustrated in Figure 5.

65 While I have shown and described the preferred embodiment of my invention, I wish it to be understood that I do not confine myself to the precise details of construction herein set forth, by way of illustration, as it is apparent that many modifications and variations may be made therein, by those skilled in the art, without departing from the spirit of the invention, or exceeding the scope of the appended claims.

70 I claim:—

75 1. In a self-adjusting dump bucket the combination with the body thereof having swinging bottom sections, a suspension yoke, bale levers thereon arms rigidly attached to the yoke and to the bucket, and a hanger above the yoke, and connected to it by the levers of a cable or chain on each side of the bucket, connected at its lower end with each of the bottom sections and means connecting it at its upper end with the hanger.

80 2. In a self-adjusting dump bucket the combination with the body thereof having swinging sections, each hinged at its outer edge to the lower part of the bucket, a suspension yoke above the bucket, arms rigidly secured to said yoke and to the bucket and a hanger above the yoke, of a cable on each side of the bucket connecting at its lower end with the hanger.

end with each of the bottom sections and at its upper end with bale levers pivotally mounted upon the suspension yoke, means connecting the bale levers with the hanger 5 and means to automatically release the bottom sections when the bucket is lowered upon the ground.

3. In a self-adjusting dump bucket the combination with the body thereof, a suspension yoke, bale levers thereon arms attached to the yoke and to the bucket, and a hanger above the yoke and connected to it by the bale levers, a cable on each side of the bucket connecting at its lower end with each 10 of the bottom sections and means for connecting it at its upper end with the hanger, of means to automatically open the bottom sections when the bucket is lowered upon the ground, and a trip device for closing the 15 bottom sections of the bucket as the latter is drawn upwardly.

4. In a self-adjusting dump bucket the combination with the body thereof having swinging bottom sections, a suspension yoke 25 above the bucket, arms rigidly secured to said yoke and to the bucket, a cable on each side of the bucket connecting at its lower end with each of the bottom sections and at its upper end with bale levers mounted upon 30 the suspension yoke and means to automatically release the bottom sections when the bucket is lowered upon the ground, of a trip device cooperating with the bale levers for closing the swinging bottom sections of 35 the bucket as the latter is drawn upwardly.

5. In a self-adjusting dump bucket the combination with the body thereof having a suspension yoke, arms rigidly attached thereto and to the bucket, a cable on each 40 side of the bucket connecting at its lower end with each of the bottom sections and at its upper end with bale levers mounted on the suspension yoke, connecting bars between said levers and the hanger, and means to 45 automatically release the bottom section when the bucket is lowered upon the ground, of a trip device cooperating with the bale levers for closing the swinging bottom sections of the bucket as the latter is drawn upwardly.

50 6. In a self-adjusting dump bucket the combination with the body thereof, a suspension yoke, arms attached thereto and to the bucket, bale levers mounted upon the

suspension yoke, a vertical swinging hanger 55 pivotally connected with the bale levers, a cable on each side of the bucket connecting it with its lower end with each of the bottom sections and at its upper end with the bale levers, means to automatically release the 60 bottom sections when the bucket is lowered to the ground, a trip device connecting with the bale levers for closing the swinging arm sections as the bucket is drawn upwardly.

7. In a self-adjusting dump bucket the 65 combination with the body thereof, a suspension yoke, arms attached thereto and to the bucket, bale levers mounted upon the suspension yoke, a vertical swinging hanger 70 pivotally connected with the bale levers, a cable on each side of the bucket connecting at its lower end with each of the bottom sections and at its upper end with the bale levers, means to automatically release the 75 bottom sections when the bucket is lowered to the ground and to automatically lock said levers in that position, and a trip device connected with the bale levers for unlocking the bale levers as the bucket is swung upward and closing the bottom sections.

8. In a self-adjusting dump bucket, the combination with the body thereof having swinging bottom sections, a suspension yoke, arms rigidly attached thereto and to the 80 bucket and a hanger above the yoke, of a cable on each side of the bucket connecting at its lower end with each of the bottom sections and at its upper end with the bale levers and track wheels mounted one on each side of the bucket to permit it to rest or 85 travel upon a track when so desired.

9. In a self-adjusting dump bucket, the combination with the body thereof having swinging bottom sections, a suspension yoke, arms attached thereto and to the bucket, bale 90 levers pivotally mounted upon the suspension yoke, a cable on each side of the bucket connecting at one end with a swinging bottom section and connecting at the other end with a bale lever, a latch plate 100 attached to the other end of each of said levers and pawls to engage said plates and hold the bottom sections in open position, of a trip device to disengage said pawls and latch plates and permit the bottom sections 105 to be closed as the bucket is drawn upwardly.

In testimony whereof I affix my signature.

GEORGE W. SLAUTER.
